DIFFERENTIAL TRANSFORMER

William D. Macgeorge, Havertown, Pa., assignor
to Automatic Temperature Control Co., Inc.,
Philadelphia, Pa., a corporation of Pennsyl-
vania

Application April 24, 1947, Serial No. 743,540

8 Claims. (Cl. 171—777)

1

This invention relates to differential trans-
formers.

There are many situations in which a differen-
tial transformer is useful for effecting controls
of various electrical circuits, especially where it
is desired to obviate "make" and "break" con-
tacts, and in a co-pending application, Serial
Number 740,507, filed April 9, 1947, I have illus-
trated such a differential transformer in connec-
tion with relay circuits, for effecting predeter-
mined actuation of relays, when a movable
armature or core attains certain attitudes rela-
tive to the transformer. In the illustrative trans-
former system of said co-pending application, the
secondaries thereof were oppositely wound, se-
ries-connected and axially aligned symmetrically on
opposite sides of a primary or exciting coil
also aligned with the secondaries, so that a single
armature or core could pass axially through and
relative to all of the aligned coils to vary the out-
put of the secondaries between voltage of A
phase, a null output and voltage of B phase, ac-
cording to the relative positioning of the movable
armature or core and the coils. A trans-
former of this type is extremely critical in op-
eration in the sense that the range of relative
movement of the armature or core to pass from
one unbalanced condition of the secondaries to
the other unbalanced condition of the secondaries
is very short indeed. The transformer device is
therefore primarily available for association
with a movable element having as the actuating
device of the armature relatively short paths
of total travel.

There are many situations in which for effi-
ciency a different form of differential transformer
should be used, especially in connection with cir-
cuits such as are illustrated in said application.
Illustratively, a modified differential transformer
should be used where the movable element actu-
ating the core has a long travel stroke.

It is among the objects of this invention: to
improve the art of differential transformers; to
provide a differential transformer with a per-
manent iron core for one of two series-connected
oppositely wound secondaries; to provide a dif-
ferential transformer in which a movable core is
provided having a long stroke in which the length
of travel of the core to and from the null point
may be much greater than has previously been
considered possible; to provide a differential trans-
former with two cores, one of which is rela-
tively permanent but adjustable in setting, and
the other of which is bodily movable to effect
changes in the output from the transformer; to

2

provide a differential transformer with two cores,
one of which may be considerably longer than
the other, the length and stroke of the latter being
limited only by the dimensions of its actuating
device; and to provide other improvements
and objects as will appear as the description pro-
ceeds.

In the accompanying drawings forming part of
this description:

10 Fig. 1 represents a fragmentary diagrammatic
section of an illustrative type of element mov-
able in accordance with the condition of a con-
ditioned device such as a rotameter, and show-
ing schematically the wiring of the transformer
of this invention.

15 Fig. 2 represents a transverse vertical section
of the transformer itself in accordance with the
preferred embodiment thereof.

20 Fig. 3 represents a horizontal section on line
3—3 of Fig. 2;

Fig. 4 represents a side elevation thereof.

The transformer 10, according to this inven-
tion is preferably formed of upper and lower
25 plates of insulating material, such as the phenolic
resin plates 13 and 14, engaging the ends of paral-
lel spaced tubular spools 15 and 16, the axial
apertures of which are in registration with cor-
responding apertures 17 and 18 in the plates 13
and 14. Secondary coils 20 and 21 are wound on
30 the respective spools and are oppositely connected
in series so as to have substantially a zero out-
put from the terminals of these secondaries,
when the magnetic reluctance of the flux paths
through these secondaries is equal, for connec-
35 tion with and into a suitable circuit. A relay cir-
cuit such as is described in said application is
preferably used. Illustratively, the output of the
secondaries is led to the primary coil 22 of a
40 transformer 23, having a secondary which is pref-
erably center-tapped for control purposes in any
desired relay or other circuit. A primary wind-
ing 25 is provided which is wrapped about the
45 secondaries on the spools between the plates,
and has terminals for connection to a suitable
source of A. C., such as line L₁, L₂. In one of the
spools, iron or related magnetizable material is
50 more or less permanently mounted, and this, illus-
tratively, may comprise a screw 26, as a per-
manent core disposed in the coil 21. The screw
55 26 may be replaced as desired with bigger or
smaller screws or screws of different lengths, as
it may be desired to predetermine the character-
istics of the differential transformer. An elon-
gated movable core which may comprise a rela-
tively thin iron rod 27 or other magnetizable ele-

ment is provided, having the free tip end 29, which core is preferably of substantially uniform mass distribution per unit of length, and arranged for guided movement through registering apertures 17 and the hollow spool 16 axially of the coil 20. The movable core is predeterminedly of such mass distribution relative to that of the fixed core 26, that with the core 27 suitably advanced into and more or less through the coil 20, there is an operative length thereof extending from the free end 29 upwardly axially or longitudinally of the armature 27, which is of maximum predetermined preponderance over the mass of the fixed armature 26 by which the induced voltage, say, of B phase, in the coil 20 is of a maximum preponderance over the opposing voltage of A phase induced in coil 21 by the fixed core, so that the resultant output is of a maximum amplitude of B phase voltage. Because of the substantially uniform mass distribution of the movable core 27 and the preferred elongation thereof, any further inward or downward movement of the movable core, moving the tip end 29 below or away from the coil 20, continues to expose a similar proportionate operative portion of the moving core to the secondary 20 so as to maintain the said maximum resultant output of B phase voltage. In other words, the core 27 is preferably longer than the effective length of the field of the secondary 20, so that after the attainment of the maximum preponderance of operative mass of the moving core 27, the same electrical value of the movable core is maintained, despite the physical relative shift of the core and secondary coil 20 in the proper direction as new operative lengths of similar mass continue to be exposed to the effective length of such field. This important characteristic enables the use of a core of practically infinite total length, any given similar length thereof constituting an "operative" portion which has the same electrical effect on its secondary as the operative portion terminating at the very tip end thereof, the only limits on the length of core 27 being practical, as determined by the maximum stroke of the element which moves as a function of the change of condition of the instant or particular conditioned device.

This gives rise broadly to three output conditions of the transformer, the first of which exists with the moving core 27 extending through and beyond its coil 20, to any degree sufficient to expose the necessary proportionate portion of its length to the field of coil 20 so as to induce a voltage of B phase preponderating in the output of the coupled secondaries. This maximum output maintains as the movable core is, illustratively, progressively moved upwardly in the coil 20, until the tip end 29 thereof coincides with the end of the effective field of the secondary. Thereafter, and with further progressive movement in the same direction, the output voltage of B phase begins to decrease, until that point is reached at which the mass of the moving core in coil 20 with a shorter extent of the core 27 in the effective field of coil 20, balances the mass of the fixed armature 26 in coil 21, and the output becomes null, because the voltages of coils 20 and 21 are mutually cancelling at this point. This is the second output condition of the transformer. With further outward or progressive movement relatively of the movable core and the transformer, as the withdrawing core 27 exposes a smaller mass to the effective field of its coil 20 than the fixed core 26 does to its secondary 21,

there is the beginning of an output from the coupled secondaries of A phase voltage, which progressively increases and reaches a maximum amplitude when the movable core has been withdrawn to a point such as to cause the tip 29 to leave the effective field of coil 20 and therefore the core has no magnetic effect upon the secondary 20. Of course, with the movable core completely withdrawn, and then progressively advanced toward, into, and through its secondary 20, there will be a reversed sequence of output conditions beginning with the maximum output of A phase, through the null point, to the maximum output of B phase, which latter maintains during further continued progression of the movable core in the same direction. Usually in setting the assembly it is preferred that the transformer be vertically adjusted along the path of travel of the movable core, until the tip end 29 of the core is so located in its coil 20 as to establish the null point at a desired predetermined position of the parts, from which movement of the movable core gives an output varying in phase according to the direction of its movement and varying in amplitude according to the degree of its movement. It is, of course, understood that the transition from one condition to another is not abrupt, but is gradual and substantially linear.

As an illustration of a mount for the movable core, reference may be made to the schematic illustrative disclosure of Fig. 1, in which a rotameter 30 is provided, arranged for movement vertically between convergent walls 31 of a flowmeter, in which the rate of flow is the condition in which the rotameter responds. With the core 27 coupled to the rotameter 30 the free end of the core 27 may have a maximum stroke vertically of the order of from one to twelve inches or more. To control the flow so as to maintain it at or about a predetermined constant, the output of the differential transformer is used as indicated by the control system of said co-pending application. It is only necessary in setting the instrument to predetermine the null point of the transformer output. This is accomplished by preliminarily adjusting the transformer 10 vertically along the path of the movement of the free end of the armature 27, so as to cause the null point in the output of the differential transformer to occur where desired in the stroke path of the core carried by the rotameter float. A mounting for such bodily shift of the transformer is shown in said application.

It being recognized that in some cases, as in the illustrative rotameter installation described, the upper end of the core 27 will be mounted in the path of fluid flow, a tube 32 of substantially non-magnetic material, such as of stainless steel, will be sealed into the lower end of the flowmeter by direct mechanical attachment or by suitable packing glands and the like, and have its upper end open to receive the core 27 as well as the fluid, while the lower end will be sealed so as to contain such fluid. The openings in the spool 16 and in the plates 13 and 14 will be so arranged as to permit the tube 32 to pass downwardly through the transformer and to permit relative vertical adjustments of the transformer 10 and the fixed tube 32, in setting the instrument.

The simplicity and cheapness of the transformer will be clear and the ease of balancing by the replaceability or adjustability of the permanent core 26, will be evident.

Having thus described my invention, I claim:

1. A differential transformer for operative association with a device having a working stroke of the order of an inch or more, comprising a primary exciting coil, two secondary coils wound and connected in series and operatively associated with the primary so that the respective outputs of the secondary coils are 180° out of phase so that with equal voltages induced in the secondary coils there is a null output therefrom, a fixed core of known inductive effect associated with one of said coils for producing a predetermined voltage output from said coil, and a core elongated relative to said fixed core having a free end and mounted for movement relative to the other of said coils and being of substantially uniform effective mass distribution longitudinally of the core and arranged when properly located relative to said other coil to expose such mass thereof to said other coil as to establish zero voltage output from the coupled secondary coils, said elongated core having such uniform mass that travel in one direction relative to its coil permits production of a predominate voltage output from said fixed core coil, and travel in the opposite direction produces a predominate voltage output in the elongated core coil, said last voltage becoming a maximum when said elongated core reaches a predetermined position different from said proper location, said maximum voltage remaining constant throughout the travel of said elongated core beyond said predetermined position in the said last mentioned direction.

2. A differential transformer for controlling an output, comprising two series-connected secondary coils wound and connected so that their respective outputs are 180° out of phase, each being hollow and having an axis, a core of known inductive mass extended at least partially into one of said secondaries, an elongated core of appreciably greater inductive mass than that of said first mentioned core movable on a path to pass through the other of said secondaries, a primary exciting coil operatively associated with both coils for symmetrically energizing both secondaries, said last mentioned movable core being arranged for movement relative to its coil, starting with a smaller effective inductive mass equal to that of the first mentioned core through exposure of an effective inductive mass greater than that of said first mentioned core such as with a continued axial movement in one direction to create successively an output from the coupled secondaries as a voltage and phase induced in that secondary coil in which the first mentioned core is disposed, a null output, and an output of voltage of the phase induced in the secondary coil relative to which the movable core moves.

3. A flowmeter comprising a device having a substantially linear stroke as a function of changes in rate of flow through the flowmeter in the range of the flowmeter, a differential transformer comprising a first and a second secondary coil the respective outputs of which are in mutually bucking opposition and said first secondary having an axial length appreciably shorter than said stroke, primary means for exciting said secondaries, an elongated core coupled to said device and movable axially along said stroke, means for guiding the core through and relative to said first secondary coil, said core having substantially uniform inductive mass distribution throughout its length and said device

having a holding point at which the free end of the core has an established relation to said first secondary at which with a given portion of the movable core of predetermined mass adjacent to said end in inductive relation to the first secondary a predetermined voltage of given phase is induced in said first secondary, a second core fixed relative to the second secondary in inductive relation thereto and of inductive mass predeterminedly equal to the inductive mass of said given portion of said movable core inducing a predetermined voltage of phase opposite to said given phase, both of said predetermined voltages being of the same amplitude so that the resultant output from the secondaries is null and constitutes a signal of attainment of the holding point, said elongated core being movable in either direction with the device to move the said free end thereof from the established point to vary the inductive masses thereof relative to that of said given portion in inductive relation to said first secondary and to vary the amplitude of induced voltage of given phase thereof relative to the predetermined voltage output of the second secondary to vary the resultant output of the secondaries in a signal of one sense or the other according to the direction of deviation of said device from the holding point according to the phase and amplitude of the resultant output.

4. In flow controlled devices, a differential transformer for operative association therewith comprising a primary exciting coil, two secondary coils connected so that their respective outputs are in bucking opposition, a fixed core entering one secondary at one end and terminating internally in spaced relation to the other end of said secondary to produce a given inductive effect in said secondary, an axially movable core for operative association with a flow-controlled device passing through said other secondary for producing a varying inductive effect therein according to its instant relation thereto as it is moved by such device, said transformer having an output depending in magnitude and phase on the relative inductive effects of the respective cores on their respective secondaries.

5. In translating devices, a differential transformer comprising a primary exciting coil, two secondaries connected so that their respective outputs are in bucking opposition, a relatively adjustable core mounted in operative inductive relation to one secondary and of adjustable inductive effect therein, a movable core having a tip end and mounted for movement relative to the other secondary and being of varying inductive effect relative thereto according to the instantaneous relative position of the tip end thereof, said movable core being appreciably longer than said fixed core and of such inductive mass distribution compared to said adjustable core as to cause an electrical indication of the position of said tip end of said movable core.

6. In a flow meter the combination of a differential transformer comprising a first and a second side-by-side axially parallel secondary coils coupled in bucking relation to furnish an output, a primary coil embracing said secondaries to energize same, connections from the primary coil for a source of oscillatory voltage, a reservoir having an inlet and an outlet passage for the flow of liquid therethrough, a tube closed at the lower end and depending from the reservoir in communication therewith and extending axially through the first secondary coil, a member in

the reservoir having a vertical working stroke therein and responsive to the flow through the reservoir to assume a level on its working stroke proportionate to the flow through the reservoir, an elongated armature core carried by said member having a free end and riding in said tube, said elongated core having an axial length at least as long as said working stroke and having said free end positionable at a given point within and axially between the ends of said first secondary when said member is at the level indicative of the predetermined flow through the reservoir, and movable in both directions from said given point axially out of said first secondary coil with appropriate changes in the level of said member, said first secondary having an output of given phase when said end is at said given point, and a fixed armature core in the other of said secondary coils for inducing an output of opposite phase and of amplitude such as to furnish with the output from said first secondary a resultant substantially null output from the secondaries when said end of said elongated armature core is at said given point within the first secondary coil, whereby an output preponderantly of one phase or the opposite phase caused by the movement of said free end from said given point produces an electrical signal.

7. In a control device the combination of a differential transformer comprising a first and a second side-by-side axially parallel secondary coils coupled in bucking relation to furnish an output, a primary coil inductively associated with said secondary coils to energize same, connections from said primary coil for a source of oscillatory voltage, an elongated armature core slidable in said first secondary and having a free end, a sensing member having a path of reciprocatory movement mounting said elongated core and having a stroke of movement longer than the axial extent of said first secondary coil so as to move said free end out of its coil in both directions with movements of the sensing member on its path, said first secondary having an output of given phase when the free end of said core is at a given point within said first coil coordinated with a desired setting of the sensing member, a fixed armature core in and shorter than the axial length of the second secondary coil for inducing an output in said second secondary of opposite phase and of amplitude to cancel the output from said first secondary and form a resultant substantial null output from the coupled secondaries when said free end of the elongated armature core is at said given point within the first secondary coil, whereby an output preponderantly

of one phase or the opposite phase caused by the movement of the free end of said core from said given point produces an electrical signal as a function of deviations of the sensing member from its desired position.

8. A signalling system for signalling the location of the free end of a movable elongated inductive mass having a free end in relation to a datum setting for said free end, comprising a hollow secondary coil A, a hollow secondary coil B, a primary winding for exciting both coils, and means coupling the coils in opposition so that their respective outputs are of substantially opposite phases and are bucking in forming a resultant signalling output, an inductive mass located in coil A and establishing a coil A output of substantially fixed known amplitude when the primary is energized with a known A. C. voltage, in combination with a movable elongated inductive mass having a free end, means for guiding the elongated mass so that the free end thereof has a path of travel coaxial with and through coil B of predeterminedly greater length than the axial length of coil B, means for moving said elongated inductive mass relative to coil B to establish three ranges of amplitudes of coil B outputs, one said range being with the free end and part of said elongated inductive mass within coil B at which the amplitude of coil B output is substantially equal to the said known amplitude of coil A output to establish a substantially null resultant output as a signal of datum location of said free end relative to coil B, the other ranges comprising movement of the elongated inductive mass so that the free end thereof moves in one sense or the other from datum whereby the amplitude of coil B output dominates or is subservient to the amplitude of coil A output to furnish a resultant output signalling the sense of departure of said free end from datum regardless of the degree of departure from datum in the given sense by movement of said free end along its said path.
